COMBINED BED AND LOUNGE

Harry B. Kulp, Highland Park, Ill., and Richard Johannes Jensen, Grand Rapids, Mich., assignors to Oxford Ltd., Chicago, Ill., a corporation of Illinois
Filed Mar. 13, 1961, Ser. No. 95,318
9 Claims. (Cl. 5—2)

This invention relates to a combined bed and lounge and more particularly to a unit including a bed pivoted at one end to swing out to a usable position.

Combined bed and lounge units have been developed in which the bed is pivoted at one end to a table structure and can be swung out about the pivot to a usable position. In order to make the unit more comfortable for daytime use as a lounge, a bolster is provided partially overlying the bed at one side thereof and serving as a back rest.

In such units it is desirable to provide the bed with a headboard adjacent to the table structure to make it more comfortable when used for sleeping. In swinging the bed out the headboard tends to interfere with the bolster so that the bolster must either be spaced sufficiently far from the headboard to clear it or must be pivoted up out of the way of the headboard when the bed is swung out. Neither of these solutions is entirely satisfactory.

Another difficulty with bed units of this type is that of pulling them out. It is in most cases difficult to grasp the bed itself to swing it out and the provision of straps or handles on the bed is not satisfactory.

It is accordingly an object of the present invention to provide a combined bed and lounge in which the bolster is slidably mounted and is connected to the bed to swing the bed from one position to another as the bolster is moved.

In one desirable construction the bolster moves away from the headboard of the bed as the bed swings out to clear the headboard without the necessity of swinging the bolster up out of the way.

According to a feature of the invention the bolster and bed are connected by a linkage which is proportioned to limit swinging of the bed to a desired position. Thus in a two bed unit the beds are prevented from moving into contact with each other so that the coverings could become pinched or bound between them.

The above and other objects and features of the invention will be more readily apparent from the following description when read in connection with the accompanying drawings, in which:

FIGURE 1 is a perspective view of a combined bed and lounge unit embodying the invention;

FIGURE 2 is a view of the wall extensions and one of the bolsters with the bed and table omitted;

FIGURE 3 is a top plan view with parts broken away and in section;

FIGURE 4 is a perspective view of an alternative type of unit embodying the invention;

FIGURE 5 is a top plan view of the unit of FIGURE 4;

FIGURE 6 is a partial horizontal section through the unit of FIGURE 4 beneath the table top;

FIGURE 7 is an elevation with parts broken away and in section of a further type of unit embodying the invention; and

FIGURE 8 is a top plan view of the unit of FIGURE 7 with parts broken away.

The unit, as shown in FIGURE 1, is adapted to fit into a corner of a room and to provide two bed and lounge units extending along adjacent walls of the room with a corner table between the units. As shown, the corner table, indicated at 10, is square with each side

2

thereof approximately equal in length to the width of beds 11 which are used therewith. The table top is elevated above the tops of the beds, as shown, and the table further includes wall extensions 12 which extend along the walls of the room from the corner. Preferably the wall extensions do not extend completely to the ends of the beds, as shown, although they could be made longer or shorter, as desired.

The beds are pivotally connected to the corner of the table diametrically opposite the corner of the room through a common hinge 13. With this type of mounting the beds may be swung individually from the full line positions shown in FIGURE 3 in which they lie parallel and adjacent to the wall of the extensions to angular positions, as shown in dot-dash lines, extending outward into the room at an angle to the walls thereof. It will be seen that the beds can be swung out to their usable position separately and individually or could, if desired, both be swung out for simultaneous use.

In order to make the beds usable as lounges and to provide comfortable seating, each of the wall extensions 12 carries a bolster 14 which projects partially over the side of the adjacent bed and which is of a size and shape to provide a comfortable back rest. Preferably the bolsters are hollow and have upholstered covers hinged thereto so that the space within the bolsters may be used for storage of pillows and extra bedding. In normal use of the unit the beds are made up completely ready for use and are covered by coverings, indicated at 15, which provide an attractive appearance and which protect the bedding when the beds are used as lounges. To use the beds for sleeping purposes, it is necessary only to swing them out about the pivot 13 to clear the bolsters, as shown in FIGURE 3, to remove the covers 15 and to take the pillows from the hollow bolsters and place them on the beds.

In order to provide comfortable beds for sleeping purposes each of the beds has a headboard 20 secured to the end thereof adjacent to the table. When the beds are swung against the wall extension for lounging use, as shown in FIGURE 1, the headboards 20 fit beneath the top of the table 10 and may blend in with the construction and design of the table. The headboards may extend completely across the beds but preferably, as shown, terminate slightly short of the sides of the beds to simplify clearing the bolsters, as described hereinafter.

According to the present invention, the bolsters are mounted on the wall extensions 12 for sliding movement toward and away from the table. For this purpose, each bolster is supported by track means which may be of the type commonly used in extension tables comprising one strip 16 secured to the wall extension and a second strip 17 slidably connected to the strip 16. If desired, more than one guiding and supporting track may be provided to hold the bolster securely on the wall extension while permitting free horizontal sliding thereof toward and away from the table.

Each of the track means extends beyond the end of the adjacent bolster and bed beneath the table and is joined by a link 18 with the headboard of the adjacent bed at a point spaced from the hinge 13.

With the beds in the lounging position, as shown in FIGURES 1 and 3, the bolsters preferably extend close to the table 10 to provide comfortable seating and the beds are closely adjacent to the wall extensions 12 with the bolsters partially overlying one side thereof. When it is desired to swing the beds out for use the bolsters may be slid away from the table, hand pulls 19 being attached to the outer ends of the bolsters to facilitate this operation. When the bolster is pulled out the track member 17 will move with it and will act through the

link 18 to swing the adjacent bed around the pivot 13. It will be noted from FIGURE 3 that movement of the bolster away from the table is sufficient to permit the headboard of the bed to clear the bolster as the bed swings out so that no interference between the headboard and the bolster occurs. Instead of pulling the bolster, the bed itself may be grasped and swung out around the pivot on suitable rollers or casters 21 provided for this purpose and the slide member 17 and link 18 will function to move the bolster away from the table as the bed is swung out so that the headboard will clear the bolster.

For returning the bed to the lounging position it may again be covered by the cover 15 and simply pushed in against the wall extension 12 about the hinge 13. During this operation the track member 17 and link 18 will return the bolster to the position shown in FIGURES 1 and 3 where it can serve as a comfortable back rest. It will be seen that these operations can all be performed very easily since the bed can be made to swing easily about the pivot 13 on its supporting casters or rollers and the bolster can slide freely and easily on the supporting track means. The only operations required are the normal ones of swinging the bed in or out or alternatively of pulling or pushing on the bolster itself. The unit can therefore be converted easily and quickly from a lounge unit to a bed unit in a very simple manner and with only a single simple operation with no possibility of interference between the parts which might scratch or damage them.

Since the beds are made up individually and must be used separately for sleeping, it would be undesirable for them to move into side-by-side contact with each other when they are swung out. Such contact would pinch or bind the bed coverings between the two beds and would tend to make them uncomfortable.

In order to prevent this, the linkage 18 is connected to the beds at a position such that they will swing through an angle less than 45° as the bolster moves through the full limits of its sliding movement. Thus, when both beds are swung out they will not move into side-by-side contact but will always have a space between them so that the coverings thereon are free.

FIGURES 4 to 6 illustrate an alternative unit having many of the features of the unit of FIGURES 1 to 3. This unit, however, is adapted for installation along a single straight wall and embodies a permanently positioned bed in addition to a convertible bed and lounge.

As shown, the unit comprises a wall board or extension 22 having a generally triangular table 23 intermediate its ends with one wall of the table supported directly on the wall extension and a leg 24 at the outer corner thereof. Additional legs, such as 25, adjacent to the wall extension may be provided if desired for additional strength and appearance.

A permanent bed 26 is secured to the wall extension 22 at one side of the table 23 and projects outward from the wall extension into the room. This bed may be of any desired permanent type of construction. A second bed 27 similar to the beds 11 of FIGURE 1 and provided with a headboard 28 is hinged to the table leg 24 by a vertical hinge 29. This bed 27 is adapted to be swung from a position, as shown in full lines in FIGURE 5, against the wall extension 22 for lounge use to an extended position, as shown in dot-dash lines for sleeping use. When the bed 27 is in its lounging position, its headboard 28 will extend partially under the top of the table 23, as shown in FIGURES 4 and 5, and when it is swung out to the sleeping position the headboard will swing out from beneath the table top.

A bolster 31, similar to the bolsters 14 of FIGURES 1 to 3 is secured to the wall extension 22 for sliding movement therealong toward and away from the table. The bolster 31 is mounted on track means of the same type as the track means of FIGURES 1 to 3, including one part 32 secured to the wall extension 22 and a second

part 33 to which the bolster is secured. The track parts extend beneath the table 23, as seen in FIGURE 6, and the outer track part 33 which is secured to the bolster is connected through a link 34 to the bed headboard 28 at a point spaced from the hinge 29.

This construction functions in exactly the same manner as the construction of FIGURES 1 to 3, the bolster moving away from the table as the bed is swung out to clear the headboard so that the bed may be moved from its lounging to its sleeping position with one simple operation.

The embodiment shown in FIGURES 7 and 8 differs from the previous embodiments and particularly from that of FIGURES 1 to 3 in that the bolster is moved toward the corner table to cause the bed to swing out rather than moving away from the corner table. In this construction, parts corresponding to like parts in FIGURES 1 to 3 have been indicated by the same reference numerals, plus 100. In this construction, two beds are arranged extending outwardly at right angles from a corner table 110 in the same manner and relationship as in FIGURES 1 to 3. The table has wall extensions 112 on which bolsters 114 are slidably mounted on track members 116 and 117 in the same manner as the corresponding constructions in FIGURES 1 to 3.

In the unit of FIGURES 7 and 8, however, the outer track member 117 is connected through a link 118 to the upper end of a lever 135 which is pivoted intermediate its ends on the back wall of the table structure. The lower end of the lever 135 is connected through a link 136 to the adjacent end of the bed 111. Also in this construction each of the bolsters 114 is spaced from the adjacent side of the table in the lounging position and the headboard of the bed shown at 120 is at the end thereof remote from the table. It will be seen that the bolster terminates closely adjacent to the headboard so that the headboard can serve as an arm rest.

To move the bed from its lounging to its sleeping position, the bolster in this instance is pushed along its track toward the table structure rather than pulled away from it. As the bolster is pushed, the lever 135 will rock counterclockwise, as seen in FIGURE 7, to push on the adjacent end of the bed spaced from its pivotal axis 113 to cause the bed to swing out to the dot-dash line position shown in FIGURE 8. Other than this reversal in the manner of operating the bolster and bed, the construction shown in FIGURES 7 and 8 is substantially similar to that of FIGURES 1 to 3.

While three embodiments of the invention have been shown and described herein, it will be understood that they are illustrative only and not to be taken as a definition of the scope of the invention, reference being had for this purpose to the appended claims.

What is claimed is:

1. A combined bed and lounge comprising a table structure having a straight wall extension at one side thereof, a bed hinged at one end to the table structure on a vertical axis spaced from said one side thereof to swing from a position adjacent and parallel to the extension to a position at an acute angle to the extension, a bolster carried by the extension partially overlying the bed at one side thereof when the bed is adjacent to the extension to serve as a back rest, means mounting the bolster on the extension for sliding longitudinally thereof, and means connecting the bolster to the bed to swing the bed about said vertical axis when the bolster is slid.

2. A combined bed and lounge comprising a table structure having a straight wall extension at one side thereof, a bed hinged at one end to the table structure on a vertical axis spaced from said one side thereof to swing from a position adjacent and parallel to the extension to a position at an acute angle to the extension, a bolster carried by the extension partially overlying the bed at one side thereof when the bed is adjacent to the extension to serve as a back rest, slidable track means mounting

the bolster on the wall extension for sliding movement therealong and projecting beyond the end of the bolster and said one end of the bed, and a linkage connecting the projecting portion of the track means to said one end at a point spaced from the hinge axis to cause the bed to swing about the hinge axis when the bolster is moved.

3. The combined bed and lounge of claim 1 in which the bed has a headboard at said one end and the connecting means so proportioned that the bolster will move away from the headboard to clear it as the bed swings away from the wall extension.

4. The combined bed and lounge of claim 1 in which the connecting means causes the bed to swing away from the wall extension when the bolster is slid toward the table structure.

5. A combined bed and lounge comprising a square table adapted to fit in a corner of a room, a pair of wall extensions projecting from adjacent sides of the table to extend along adjacent walls of the room, a pair of beds each of a width equal to the length of a side of the table, vertical hinge means connecting the beds at a corner of each to the corner of the table spaced from said adjacent sides whereby the beds can swing from positions adjacent to said wall extensions respectively to positions at acute angles to the wall extensions, bolsters carried by the wall extensions and partially overlying the beds respectively when the beds are adjacent to the wall extensions to serve as back rests, means mounting the bolsters on the wall extensions for sliding movement toward and away from the table, and means connecting each of the bolsters to the adjacent bed to swing the bed about the vertical hinge means when the bolster is moved.

6. The combined bed and lounge of claim 5 in which the connecting means cause the beds to swing away from the wall extensions when the bolsters are moved toward the table.

7. The combined bed and lounge of claim 5 in which each bed has a head board at one end and the connecting means so proportioned that the bolsters will move away from the headboard to clear them as the beds swing away from the wall extension.

8. A combined bed and lounge comprising a table adapted to fit against a wall, a wall extension projecting from the table at one side thereof and adapted to fit against the same wall, the table top having one edge joining the wall extension at an obtuse angle thereto and a leg at the end of said edge remote from the wall extension, a bed hinged at one end to said leg to swing from a position adjacent to the wall extension with a portion thereof beneath said edge of the table top to a position at an acute angle to the wall extension, a bolster mounted on the wall extension for horizontal sliding movement thereon toward and away from the table, and means connecting the bolster to the bed to swing the bed away from the wall extension when the bolster is moved away from the table.

9. The combined bed and lounge of claim 8 in which the bed has a headboard at said one end movable beneath the table top and the connecting means so proportioned that the bolster will move away from the headboard to clear it when the bed is swung away from the wall extension.
